SPADE BIT

William Southall, deceased, late of Moonah, Tasmania, Australia, by Dorothy L. Southall, administratrix, Moonah, Tasmania, Australia, assignor to The Stanley Works, New Britain, Conn.

Filed Feb. 11, 1974, Ser. No. 441,174

Term of patent 14 years

Int. Cl. D8—03

U.S. Cl. D54—4

FIG. 1

FIG. 2

FIG. 3

FIG. 4

FIG. 5

FIG. 1 is a perspective view of a spade bit showing the new design;

FIG. 2 is a top view thereof;

FIG. 3 is a side elevational view thereof, the opposite side being a minor image thereof;

FIG. 4 is an end view of the bit end or left hand end as seen in FIG. 1; and

FIG. 5 is an end view of the shank end or right hand end as seen in FIG. 1.

The novel features of the design reside in the combination of the blade body with its angled leading edges and the diamond-shaped guide point which is characterized by a pyramidal outer portion and reduced throat portion adjacent the leading edges of the body of the blade.

What is claimed is:

The ornamental design for a spade bit, as shown and described.
